United States Patent Office.

R. A. COWELL, OF CLEVELAND, OHIO, ASSIGNOR TO HIMSELF AND E. N. KEYS, OF SAME PLACE.

Letters Patent No. 97,480, dated December 7, 1869.

IMPROVEMENT IN PUSHING-JACKS FOR RAILROAD-CARS.

The Schedule referred to in these Letters Patent and making part of the same.

To all whom it may concern:

Be it known that I, R. A. COWELL, of Cleveland, in the county of Cuyahoga, and State of Ohio, have invented a certain new and improved Car-Motor; and I do hereby declare that the following is a full and complete description of the same, reference being had to the accompanying drawings, making a part of this specification, in which—

Figure 1 is a side view.

Figure 2 is a detached section, that will be referred to in the description.

Like letters refer to like parts.

The nature of this invention relates to the construction of a device for a car-motor, to be operated by one man, in moving heavy or loaded cars, by which the labor is speedily and easily performed, and consists of a lever, having attached two staves, so arranged that they operate in a walking manner, one staff holding the car in place, or preventing its backward movement, while the other is carried forward.

In the drawing—

A represents a lever, one end of which is curved downward, as represented, and to which is jointed at *a* the head-block B. This head-block is provided with a shoulder, in which the corner of the car rests.

To this head-block B is jointed a walking-staff, C.

D is a similar staff, being jointed to the lever A, as seen.

The lower ends of these staves are provided with metallic feet, I I, having sharp edges, so that when placed on the flange of the rail, they cut into said rail sufficiently to hold them from slipping or being moved backward by the weight of the car.

b b are springs secured to the staves, and extend down on the opposite side of the rail from the feet, as seen in the drawing. The object of these springs is to keep the feet on the flange of the rail.

Fig. 2 is a longitudinal section of the head-block B, showing the slots E F.

In these slots are pivoted the dogs G H, the object of which is to fasten the head-block to the car, as shown in fig. 1, in which J represents a portion of a car, the points *z z* of the dogs catching in said car.

The device is placed in the position shown in fig. 1; the shoulder placed under the corner of the car, as stated; then, by a slight depression of the lever A, the dog E is thrown so as to catch into the car, and, by still depressing the lever, the flange *c* of the lever will strike against the dog F, and force that into the car, thus holding it secure while being propelled.

By working the lever up and down, the staves C D are alternately caused to hold fast upon the rail, thus forming a fulcrum, and the car is carried forward, and, at the same time, the staff, not acting as a fulcrum, is made to move forward, and, in its turn, becomes a fulcrum. By this means, the staves are performing a walking-operation, the one holding what the other gains, and prevent the liability of the car falling back in case of moving up a grade.

It will also be observed, that by making the lever curved, as shown, when operating, it does not perform a lifting action as much as a pushing forward.

By the use of this device, one man is able to perform, with great ease and rapidity, the work of several men.

What I claim as new, and desire to secure by Letters Patent, is—

The self-adjusting dogs E F, and head-block B, in combination with the lever A and the walking-staves C D, having the sharp-edged metal feet I and springs *b b*, all arranged as herein set forth.
